UNITED STATES PATENT OFFICE.

CHARLES L. MICHOD, OF CHICAGO, ILLINOIS.

METHOD OF LOADING FREIGHT-CARS.

1,263,788.

Specification of Letters Patent. Patented Apr. 23, 1918.

Application filed December 26, 1917. Serial No. 208,950.

To all whom it may concern:

Be it known that I, CHARLES L. MICHOD, a citizen of the United States, residing at Chicago, in the county of Cook and State of Illinois, have invented a new and useful Improvement in Methods of Loading Freight-Cars, of which the following is a specification.

My invention relates more particularly to an improved method of loading heavy articles, such as automobiles, upon cars and more especially box-cars, to the end that cars may be loaded expeditiously and relatively economically and as nearly as possible the maximum amount of space afforded by the car, utilized for the storing of the articles to be transported.

Generally stated, my improved method as practised in connection with box-cars, involves the entering of the article to be transported, into the car through the central opening thereof, thereupon elevating the article by any suitable mechanism and then introducing suitable supporting means under the article while the latter is in elevated position and thereafter moving the supporting means with the article thereon into one end of the car.

Referring to the accompanying drawings:

Figure 1 is a view in longitudinal, sectional elevation of a box-car loaded with automobiles by my improved method, as I prefer to practise it, a portion of one section of a guide rail for the racks being omitted. Fig. 2 is a plan section of the car with the automobiles omitted. Fig. 3 is an enlarged section taken at the line 3 on Fig. 1 and viewed in the direction of the arrow. Fig. 4 is a plan view of one of the supporting racks employed and planking supported thereby. Fig. 5 is an enlarged section taken at the line 5—5 on Fig. 4 and viewed in the direction of the arrows; and Fig. 6, a view in elevation, partly broken, of the rack of Fig. 5 showing it as viewed from the righthand side of this figure.

In carrying out my method, as I prefer to practise it, in connection with the loading of box-cars with automobiles, one of the automobiles to be transported is caused to enter the car through one of the side openings thereof, one of these openings being shown at 7 and the automobile caused to extend lengthwise of the car opposite the opening through which it is entered. The automobile so entered is then elevated above

the floor 8 of the car, by any suitable means, as for example the block and tackle mechanisms illustrated at 9 and preferably provided of four in number which are support- 60 ed in a rectangular arrangement, as indicated by dotted lines in Fig. 2 and hook over the hubs of the wheels of the automobile. While the automobile is thus suspended, any

suitable form of means constructed to support the weight of the automobile and adapted to be shifted with the automobile thereon into the end of the car, are positioned under the elevated automobile to support the latter, the tackle devices 9 then released from the automobile and the supporting means referred to with the automobile thereon moved into the end of the car, thus supporting the automobile referred to in

elevated position in one end of the car and 75 at such a height, where the car is to be loaded with automobiles in superposed relation, as to permit another automobile introduced into the car through one of its side openings to be positioned under the first-referred-to automobile, as illustrated of either 80 end of the car in Fig. 1. Another automobile to be loaded is then introduced into the car through one of its side openings, and positioned to extend lengthwise of the car, then 85 elevated as hereinbefore described, and supporting means of the character hereinbefore referred to positioned under the dependingly supported automobile, the tackle mechanism 9 released and the supporting means with the 90 automobile thereon then moved into the opposite end of the car, as explained of the first-referred-to automobile, and another automobile entered into the car to be positioned beneath it. Another automobile to be loaded 95 is then entered into the car and elevated as explained above, thus affording a space below it for a sixth automobile, it being preferred that supporting means of any desirable character be positioned under the last 100 automobile elevated, as stated, for supporting the latter. The arrangement of the automobiles in the car upon loading it, as above stated, is that shown in Fig. 1 and it will be readily apparent that the full capacity of the car for storing automobiles, is 105 utilized.

While the form of supporting means for the automobiles is immaterial so far as my present invention is concerned, I prefer to 110 use racks such as those illustrated, which are provided in pairs for each elevated automo-

bile. The rack members shown, each comprise two end-frames 10 spaced apart crosswise of the car and a cross-frame 11 connecting the end-frames together. The end-frames 5 are formed of upright bars 12 connected together at their lower ends by a cross-piece 14 with braces 15 connected with the cross-piece 14 and the uprights 12 and a cross-piece 16 connecting the uprights 12 intermediate 10 their ends. The cross-frame 11 is formed of bars 17 extending crosswise of the car and rigidly connected at their opposite ends with the uprights 12, the bars 17 supporting members 18 spaced apart to afford 15 channels, the bottoms of which are formed of downwardly curved bars 19 connected with the bars 17, these channels being provided for the reception of the wheels of the automobile supported thereby, as shown in 20 the drawings.

By preference, flanged rails, which may be formed of angle-iron and represented at 20 are laid upon the floor of the car to extend in spaced relation and lengthwise thereof, as 25 represented in Fig. 2, the racks referred to resting at their cross-pieces, or bases, 14 upon the channeled portions of the rails 20 which facilitates the sliding of the racks, with the automobiles supported thereon, into 30 the ends of the car, the rails 20 preferably having their flanged portions extending adjacent the outer sides of the racks.

The racks of each pair thereof are shown as supporting planking 21 which would be 35 provided where the articles to be supported thereby in elevated position above the floor of the car, are of such form or character that a broad area of supporting surface therefor, is necessary or desirable.

40 While I have described my invention in connection with the loading of a car with automobiles only, and have shown a particular apparatus for this purpose, I do not wish to be understood as intending to limit it 45 thereto, as the invention may be utilized in the loading of a car with other articles than automobiles or with a combination of automobiles and other articles, and any other suitable apparatus may be used in carrying 50 out the steps of my invention.

What I claim as new and desire to secure by Letters Patent is—

1. The method of loading relatively heavy 55 articles into freight cars, which consists in entering the article into the car through the

central opening of the latter, thereupon elevating the article, and introducing supporting means under the article while the latter is in elevated position, and thereafter moving the supporting means with the article 60 thereon into one end of the car.

2. The method of loading relatively heavy articles into freight cars, which consists in entering the article into the car through the central opening of the latter, thereupon elevating the article, and introducing supporting means under the article while the latter is in elevated position, and thereafter moving the supporting means with the article 65 thereon into one end of the car, and entering another article into the car through the central opening of the latter, elevating the article and introducing supporting means under the article while the latter is in elevated position and thereafter moving the 70 supporting means with the article thereon into the opposite end of the car.

3. The method of loading relatively heavy articles into freight cars, which consists in entering the article into the car through the 80 central opening of the latter, thereupon elevating the article, and introducing supporting means under the article while the latter is in elevated position, and thereafter moving the supporting means with the article 85 thereon into one end of the car, and entering another article into the car through the central opening of the latter, elevating the article and introducing supporting means under the article while the latter is in elevated position and thereafter moving the 90 supporting means with the article thereon into the opposite end of the car, entering another of the articles to be transported, into the car through the central opening of the 95 latter thereupon elevating this article and supporting the latter in elevated position above the bottom of the car.

4. The method of loading relatively heavy articles upon freight cars, which consists in 100 elevating the article to be loaded upon the car, to extend above a portion of the car, introducing supporting means under the article while the latter is supported in elevated position, and thereafter moving the supporting means with the article thereon into 105 another location on the car for supporting said article during its transportation on the car.

CHARLES L. MICHOD.
